GUIDED MISSILE

Otho E. McCrackin, Overland, Mo., assignor to the United States of America as represented by the Secretary of the Navy

Filed May 4, 1949, Ser. No. 2,424

Term of patent 14 years

(Cl. D71—1)

FIG. 1

FIG. 4

FIG. 2

FIG. 3

FIG. 1 is a perspective view of the guided missile as it would appear when seen obliquely from the underside at the front;

FIG. 2 is a perspective view of the guided missile as it would appear when seen obliquely from above at the rear;

FIG. 3 is a side elevation of the guided missile;

FIG. 4 is an exploded view thereof.

The characteristic features of my guided missile design comprise the petalled appearance of the fore end of the sabot and the adjacent perforated portion of the long, pencil-like projectile, augmented by the system of slots in the sabot and the fins of the projectile which emerge from the slots from a place adjacent to the concentric ribs in the head.

What is claimed is:

The ornamental design for a guided missile, substantially as shown and described.
